UNITED STATES PATENT OFFICE.

CLIFFORD A. THOMAS, OF YAKIMA, WASHINGTON.

SKATE.

Application filed January 7, 1925. Serial No. 1,065.

To all whom it may concern:

Be it known that I, CLIFFORD A. THOMAS, a citizen of the United States, and resident of Yakima, in the county of Yakima and 5 State of Washington, have invented certain new and useful Improvements in Skates, of which the following is a specification.

My invention relates to improvements in skates of the type having a body mounted on 10 wheels, and it consists in the combinations, constructions and arrangements herein described and claimed.

More specifically defined, the present invention contemplates the provision of a 15 skate comprising a foot plate or body which is supported on two wheels, one positioned in advance of the other.

An object of the present invention is the 20 provision of a skate of the character described which affords facilities for securing and staying the skate body to the foot of a wearer so that play between the foot of the wearer and the skate is precluded and the use of the skate in an ordinary manner does 25 not cause any twisting or side stress on the foot of the wearer.

A further object of the invention is the 30 provision of a skate of the character described which is adapted to be secured firmly to the foot of a wearer without causing any discomfort to the wearer.

A still further object of the invention is the 35 provision of a skate of the character described having means for protecting and shielding the wheels thereof to prevent contact of the wheels of the skate on one foot with the skate on the other foot of a user.

Other objects and advantages will be apparent from the following description, considered in conjunction with the accompanying 40 drawings, in which—

Figure 1 is a side elevation of a skate embodying the invention.

Figure 2 is a plan view of the skate and

Figure 3 is a longitudinal vertical section 45 through the skate, the wheels thereof being shown in elevation.

The body of the skate comprises a foot 50 plate consisting of a front section 1 and a rear section 2, the front section slidably overlapping the rear section and the lapped portions of the front and rear sections having vertically aligned slots 3 and 4 respectively extending longitudinally of the sections.

Bolts 5 extends through the aligned slots

and nuts 6 in threaded engagement with the bolts can be tightened to clamp the sections together with the effective length of the body of the skate adjusted within a considerable range, as desired. 60

The back section 2 is downwardly offset at an appreciable distance from its rearward end, as indicated at 7 to provide a socket for the reception of the heel of the shoe of a 65 wearer of the skate. An upstanding brace for engaging with the rear portion of the shoe of the wearer is indicated at 8 and is secured to the rearward portion of the offset part of the back section 2 in any suitable 70 known manner, as by being formed with a rearwardly turned flange 9 which rests flatwise upon the offset portion 7, the flange 9 and the underlying portion of the back section 75 of the foot plate having vertically aligned openings for the reception of bolts, such as indicated at 10, the bolts having nuts, as indicated at 11 screwed thereon. The lower end portion of the bracing member 8 is enlarged laterally, as indicated at 12 and is curved in horizontal sectional contour to conform to the curvature of the heel 80 portion of the shoe of a wearer.

The rearward end portion of the front 85 section 1 of the foot plate curves rearwardly and upwardly adjacent to the rear end of the slot 3 and then extends horizontally as indicated at 13 slightly beyond the vertical line of the forward end of the downwardly offset portion 7 of the back section 2 and 90 then is bent to extend vertically downward as at 14 to engage at its end with the offset portion 7. The portion 13 of the front section is adapted to underlie the instep portion of the shoe of a wearer and to closely 95 contact with the arched portion of the sole of the shoe while the vertical portion of the front section is adapted to bear against the front side of the heel of the shoe of the wearer. 100

The front section 1 of the foot plate can be slid rearwardly on the forward portion of the back section of the foot plate until the heel of the shoe of the wearer is clamped between the end portion 14 of the front section and the enlarged portion 12 of the bracing member at the rear of the downwardly offset portion 7 of the back section. 105

The forward end portion of the front section 1 of the foot plate is arched longitudinally substantially along the arc of a circle as indicated at 15 and the arched portion 15 110

is formed with a pair of integral side members, as at 16, thus producing a protective hood or housing at the forward end of the skate body. This protective housing is open at its lower end which terminates substantially in the plane of the forward end portion of the front section 1 and the side members 16 are provided adjacent to their lower edges with aligned bearings for a front axle 17 which carries a wheel 18. The axis of the axle 17 is located above the level of the front section 1 of the foot plate but the wheel 18 is of sufficient diameter to protrude from the protective hood through the opening at the lower side thereof for rolling engagement with a level surface 19.

The back section 2 has the rearward end portion thereof arched longitudinally substantially along the arc of a circle, as indicated at 20. The arched portion 20 is provided with side members 21, the side members 21 being formed with aligned bearings for a rear axle 22 which carries a rear wheel 23. The arched portion 20 and side members 21 provide a protective hood or housing for the rear wheel which depends through the opening at the lower side of the protective housing for rolling engagement with the surface 19, which of course may be a floor, the ground or a like surface.

A front bracing member for engaging with the upper and forward portions of the shoe of a wearer has the form of an elongated strip 24 secured firmly at its forward end, as at 25 and 26 to the arched portion 15 of the front of the skate body, the bracing strip 24 being curved to closely contact at all points along the free part thereof with the upper portion of the instep of the shoe of a wearer and to extend upwardly along the front side of the ankle portion of the shoe. The front bracing strip 24 is provided at intervals along its length with pairs of lateral loops as indicated at 27, 28, 29 and 30 respectively. The front section 1 is provided with pairs of lateral loops 31 and 32 respectively adapted to cooperate with the loops 27 and 28 to engage with fastening straps 33 and 34 respectively. The enlarged lower end portion 12 of the brace 8 is provided with a pair of lateral loops 35 for cooperating with the loops 29 to engage with snaps, as at 36 and the upper end portion of the bracing member 8 is provided with a pair of lateral loops 37 for cooperating with the loops 30 to engage with straps, as at 38. The bracing members 24 and 8 preferably are made of metal of considerable flexibility. A pad 39 of leather or like material underlying the front bracing member 24 while a similar pad 40 provides a facing for the inner side of the bracing member 8, the respective pads 39 and 40 extending laterally of the bracing members with which they are associated.

From the foregoing description of the various parts of the device, the operation thereof may be readily understood. The provision of the heel socket and the hereinbefore described means for securing the 70 skate body to the foot of a wearer permits the skate body to be secured firmly to the foot of a wearer without discomfort to the wearer so that play will be prevented between the skate body and the shoe of a 75 wearer and therefore the act of skating can be accomplished with but very little fatigue and without causing strain of the muscles or ligaments of the foot of the wearer. The 80 construction of the skate body and the provision of the means for securing the skate body to the foot of the wearer assures good balance of the wearer on a pair of the skates. The provision of the protective hood for the wheels of the skate prevents interference of the wheel of one skate with the other 85 skate at any time during skating operations.

I claim:—

1. A skate of the character described comprising a foot plate consisting of a rear section having the rear end portion thereof downwardly offset, a front section slidably overlapping the front portion of the rear section, said lapped portions having vertically aligned slots extending longitudinally 95 thereof, means extending through said slots for clamping said sections together in adjusted position in respect to one another, a rear bracing member upstanding from the downwardly offset portion of the rear section of the foot plate, said bracing member having the lower end portion thereof laterally enlarged and curved to conform to the curvature of the heel portion of a shoe of the wearer, the rearward end portion of the front section being curved upwardly and rearwardly from the rear end of the slot therein to closely contact with the arch portion of the sole of a shoe of the wearer and having the extreme rearward end portion thereof bent downwardly to engage at its end with the downwardly offset portion of the rear section of the foot plate and for engaging with the front face of the heel of a shoe of the wearer, and means for securing said foot plate to the foot of a wearer, said securing means including a front bracing member comprising an elongated strip carried by the front section of said foot plate and extending rearwardly and upwardly for engagement with the upper and forward portion of the foot and ankle of a wearer.

2. A skate of the character described comprising a foot plate consisting of a rear section having the rear end portion thereof downwardly offset, a front section slidably overlapping the front portion of the rear section, said lapped portions having vertically aligned slots extending longitudinally 125 of

- thereof, means extending through said slots for clamping said sections together in adjusted position in respect to one another, a rear bracing member upstanding from the 5 downwardly offset portion of the rear section of the foot plate, said bracing member having the lower end portion thereof laterally enlarged and curved to conform to the curvature of the heel portion of a shoe of the wearer, the rearward end portion of the front section being curved upwardly and rearwardly from the rear end of the sole of a shoe of the wearer and having the extreme 10 rearward end portion thereof bent downwardly to engage at its end with the downwardly offset portion of the rear section of the foot plate and for engaging with the front face of the heel of a shoe of the wearer, and means for securing said foot plate to the 15 foot of a wearer, said securing means including a front bracing member comprising an elongated strip carried by the front section of said foot plate and extending rearwardly and upwardly for engagement with the upper and forward portion of the foot and ankle of a wearer, said bracing members being formed of metal possessing considerable flexibility, and leather pads for the bracing members.
- 20 3. A skate of the character described comprising a foot plate consisting of a rear section having the rear end portion thereof downwardly offset, a front section slidably overlapping the front portion of the rear section, said lapped portions having vertically aligned slots extending longitudinally thereof, means extending through said slots for clamping said sections together in adjusted position in respect to one another, a rear bracing member upstanding from the 25 downwardly offset portion of the rear section of the foot plate, said bracing member having the lower end portion thereof laterally enlarged and curved to conform to the curvature of the heel portion of a shoe of the wearer, the rearward end portion of the front section being curved upwardly and rearwardly from the rear end of the slots 30 therein to closely contact with the arch portion of the sole of a shoe of the wearer and having the extreme rearward end portion thereof bent downwardly to engage at its end with the downwardly offset portion of the rear section of the foot plate and for engaging with the front face of the heel of a shoe of the wearer, and means for securing said foot plate to the foot of a wearer.
- 35 4. A skate of the character described comprising a foot plate consisting of a rear section having the rear end portion thereof downwardly offset, a front section slidably overlapping the front portion of the rear section, said lapped portions having vertically aligned slots extending longitudinally thereof, means extending through said slots for clamping said sections together in adjusted position in respect to one another, a rear bracing member upstanding from the 40 downwardly offset portion of the rear section of the foot plate, said bracing member having the lower end portion thereof laterally enlarged and curved to conform to the curvature of the heel portion of a shoe of the wearer, the rearward end portion of the front section being curved upwardly and rearwardly from the rear end of the slots 45 therein to closely contact with the arch portion of the sole of a shoe of the wearer and having the extreme rearward end portion thereof bent downwardly to engage at its end with the downwardly offset portion of the rear section of the foot plate and for engaging with the front face of the heel of a shoe of the wearer, and means for securing said foot plate to the foot of a wearer.
- 50 5. A skate of the character described comprising a foot plate consisting of a rear section having the rear end portion thereof downwardly offset, a front section slidably overlapping the front portion of the rear section, said lapped portions having vertically aligned slots extending longitudinally thereof, means extending through said slots for clamping said sections together in adjusted position in respect to one another, a rear bracing member upstanding from the 55 downwardly offset portion of the rear section of the foot plate, said bracing member having the lower end portion thereof laterally enlarged and curved to conform to the curvature of the heel portion of a shoe of the wearer, the rearward end portion of the front section being curved upwardly and rearwardly from the rear end of the slots 60 therein to closely contact with the arch portion of the sole of a shoe of the wearer and having the extreme rearward end portion thereof bent downwardly to engage at its end with the downwardly offset portion of the rear section of the foot plate and for engaging with the front face of the heel of a shoe of the wearer, and means for securing said foot plate to the foot of a wearer.

CLIFFORD A. THOMAS.
